Primary Examiner — Lucy Lieberman(74) Attorney, Agent, or Firm — Howard Natter; Natter & Natter(57) CLAIM

The ornamental design for a watch, as shown and described.

DESCRIPTION

FIG. 1 is a front right side perspective view of a watch showing my new design;

FIG. 2 is a right side elevational view thereof;

FIG. 3 is a top plan view thereof;

FIG. 4 is a front elevational view thereof;

FIG. 5 is a left side elevational view thereof; and,

FIG. 6 is a rear elevational view thereof.

The bottom plan view is a mirror image of the top plan view. The broken lines in the drawings are used to show unclaimed portions of the watch and an unclaimed watch band.
